Primary Examiner — Darlington Ly*Assistant Examiner* — Giang Hoang Tran(74) *Attorney, Agent, or Firm* — Avez IP, LLC(57) **CLAIM**

The ornamental design for a golf cart side panel, as shown and described.

DESCRIPTION

FIG. 1 is a top, front and left side perspective view of a golf cart side panel;

FIG. 2 is a top, rear and right side perspective view thereof;

FIG. 3 is a left side elevation view thereof;

FIG. 4 is a right side elevation view thereof;

FIG. 5 is a front elevation view thereof;

FIG. 6 is a rear elevation view thereof; and,

FIG. 7 is a top plan view thereof.

In FIGS. 1-7, dot-dot lines indicate environmental structure that forms no part of the claimed design. The dot-dash lines in FIGS. 1-5 and 7 are provided for annotative purposes only to show the bounds of the claim. The dot-dash lines do not illustrate structures or subject matters and do not form part of the claimed design.

1 Claim, 7 Drawing Sheets(56)
